OF MASSACHUSETTS.

SURFACE-GRINDING MACHINE.

1,138,289.

Specification of Letters Patent. Patented May 4, 1915.

Application filed January 15, 1915. Serial No. 2,467.

To all whom it may concern:

Be it known that we, JAMES N. HEALD and ALDEN M. DRAKE, citizens of the United States, both residing at Worcester, in the county of Worcester and State of Massachusetts, have invented a new and useful Surface-Grinding Machine, of which the following is a specification.

This invention relates to a surface grinding machine of the type in which the work is supported upon a movable work table.

It is the object of our invention to improve the arrangement and mechanical construction of such machines, having reference particularly to the mechanisms for vertically adjusting and for driving the grinding wheel.

Further features of our invention relate to improved devices for controlling the lateral movements of the grinding wheel and for moving the work table.

With these and other objects in view our invention further relates to certain devices, arrangements and combinations of parts which will be hereinafter described and more particularly pointed out in the appended claims.

A preferred form of our invention is shown in the drawings in which—

Figure 1 is a front elevation of our improved machine; Fig. 2 is a sectional detail taken along the line 2—2 in Fig. 1; Fig. 3 is a rear elevation of the machine; Fig. 4 is an enlarged detail of the support for the idle pulleys; Fig. 5 is an end elevation of the machine; Fig. 6 is a top plan view thereof; Fig. 7 is an enlarged rear elevation of the wheel slide and a portion of the belt drive; Fig. 8 is a front vertical sectional view of the wheel slide taken along the line 8—8 in Fig. 5; Fig. 9 is a horizontal section of the bearings and support for the grinding shaft taken along the line 9—9 in Fig. 8; Fig. 10 is a detail elevation of the devices for manually adjusting the grinding shaft bearings, taken substantially along the line 10—10 in Fig. 5; Fig. 11 is an end elevation of the mechanism for raising and lowering the movable head which supports the wheel slide; Fig. 12 is a top plan view of a portion of the movable head and its support; Fig. 13 is a detail view of a portion of the hand elevating devices looking in the direction of the arrow 13 in Fig. 11; Fig. 14 is an elevation of the upper bearing

of the elevating shaft; Fig. 15 is a partial end elevation, partly in section, showing the cross feed mechanism; Fig. 16 is a horizontal sectional view of the table feeding mechanism; Fig. 17 is a detail elevation of a portion of said mechanism; Fig. 18 is a rear elevation, partly broken away, showing the speed-changing and reversing mechanism for the table feed, the view being taken as indicated by the arrow 18 in Fig. 16; Fig. 19 is a sectional detail of the change gear mechanism taken along the line 19—19 in Fig. 16; Fig. 20 is an enlarged detail section of the friction drive at one end of the table feeding shaft; Fig. 21 is a vertical sectional view of the table-feed-controlling mechanism taken along the line 21—21 in Figs. 1 and 16; Fig. 22 is a diagrammatic view showing the relative positions of the hand and power feed shafts; Fig. 23 is a sectional view showing the connections from the hand wheel to the table driving gear taken along the line 23—23 in Fig. 22, and Figs. 24 and 25 are detail views, in front and side elevation, of a portion of the friction connection between the table drive and the cross feed.

Referring to the drawings, our improved grinding machine is mounted upon a base (Fig. 1) having a standard 31 rigidly secured thereto by a plurality of bolts 32 (Fig. 6). A head 33 is mounted for vertical movement upon the standard 31 and constitutes a support for the wheel slide 34 (Fig. 7). The grinding wheel W is mounted upon a horizontal shaft 35 (Fig. 9) having a longitudinally extended drum 36 secured thereto.

Wheel driving mechanism.—The main power shaft of the machine is indicated at 37 (Fig. 3) and may be driven in any convenient manner. As shown in the drawings, the shaft 37 carries a pulley 38 which is driven by a belt 39 from a motor 40. The shaft 37 is also provided with a pulley 41 which drives a belt 42. The belt 42 passes around a guide pulley 43 mounted for vertical adjustment upon the standard 31 and thereafter passes around an idle pulley 44 mounted upon the movable head 33. From the pulley 44 the belt 42 passes over the drum 36 and from thence to a second idle pulley 45 mounted upon a bracket 46 (Figs. 4 and 7) secured to the head 33 by bolts 47. In practice, the pulleys 44 and 45 are both commonly supported upon the bracket 46. 110

The pulleys 41, 43, 44 and 45 are so positioned that the runs of the belt 42 between the pulleys 43 and 44 and between the pulleys 45 and 41 extend in substantially vertical lines parallel to the travel of the head 33. With this arrangement it will be seen that the length of the driving belt may remain unchanged, whatever the vertical position of the head 33. It will also appear that this construction enables me to use a single long driving belt between the wheel shaft and the main power shaft and that this belt is so arranged that it will have driving contact with a large portion of the circumference of the drum 36.

Head elevating mechanism.—Referring particularly to Figs. 7, and 11 to 14, we will now describe the movable head and the mechanism for elevating it. The movable head 33 is provided with undercut guiding surfaces 50 and 51 (Fig. 12) upon its rear face, which surfaces engage ways 52 upon the standard 31. The guiding surface 51 is formed upon an adjustable gib 53. Clamping screws 54 (Fig. 2) extend through the gib into the head 33 and are provided with handles 55 for convenient operation thereof. The screws 54 are loosened during vertical adjustment of the head and are thereafter tightened to rigidly secure the head to the standard 31 during the grinding operation.

An elevating screw 56 (Fig. 5) is supported at its upper end in an anti-friction thrust bearing 57 (Fig. 14) secured to the standard 31. The shaft 56 is threaded throughout the greater portion of its length and engages a nut 58 mounted upon the rear face of the head 33 as shown in dotted lines in Figs. 7, 11 and 12. The lower end of the shaft 56 slides freely through a sleeve 59 (Fig. 11) rotatably mounted in the base 30. At its lower end, the sleeve carries a beveled gear 60 and is held in position in its bearing by a collar 610 and an adjusting nut 620 at its upper end. Relative rotation of the sleeve 56 and the sleeve 59 is prevented by the key 630 fixed in the shaft 56 and sliding in a keyway 640 in the sleeve 59. The beveled gear 60 engages a second beveled gear 61 (Fig. 11) mounted upon a shaft 62 extending horizontally through the base 30 to the front of the machine. At its forward end, the shaft 62 carries a spur gear 63 engaging a second spur gear 64 (Fig. 13) upon a short stud shaft 65. The shaft 65 is squared at its outer end, as indicated at 66, for the reception of an operating handle.

The operation of the head elevating devices will be apparent from the detailed description thereof.

While it is possible to finally adjust the machine for certain purposes by the use of the elevating devices just described, it is my intention to use these devices merely for

rough or approximate adjustment, the final close adjustment being made by an auxiliary adjusting mechanism which will now be described.

Auxiliary vertical adjustment.—Referring particularly to Figs. 9 and 10, the wheel shaft 35 is mounted in bearings 70, 71 and 72. The bearing 70 is mounted in an eccentric sleeve 73 rotatable in the wheel slide 34. The sleeve 73 has integral therewith a longitudinally extending arm 74 secured at its outer end to a second eccentric sleeve 75 which supports the bearings 71 and 72. The arm 74 insures simultaneous and equal angular movements of the sleeves 73 and 75.

Intermediate its ends the sleeve 75 carries a segment gear 76 (Fig. 10) positioned to engage a worm 77 upon the lower end of an inclined shaft 78 carried by the slide 34. At its upper end the shaft 78 is connected by beveled gears 79 and 80 to a cross shaft 81 having a hand wheel 82 (Fig. 5) upon its outer end. The hand wheel 82 may be graduated around its circumference, as shown in Fig. 1, and the slide 34 may carry a zero line upon a stud 82^a adjacent the hand wheel 82. The arm 74 may of course be formed integral with both sleeves 73 and 75 if so desired.

Reference to Fig. 10 will show the extreme eccentricity of the sleeve 75 the centers of the shaft 35 and the sleeve 75 being about 1" apart, so that the axis of the shaft 35 moves in the arc of a 2" circle when the sleeve 75 is adjusted. Adjustment of the bearing to carry the axis of the shaft $\frac{1}{8}$ " above or below its normal position is found to be ample for practical purposes, and for this range of movement the arc is substantially a straight line and the vertical movement is substantially proportional to the angular movement of the hand wheel 82 as measured by the graduations thereon.

Not only may very accurate adjustment be thus obtained but furthermore the elevation or depression of the shaft through angular adjustment of the eccentric sleeves in close fitting bearings avoids the lost motion between screw and nut and the varying friction of a vertically sliding member, and also avoids the necessity of raising or lowering the great mass of the movable head and wheel slide for fine adjustments, all of which is unavoidable in using elevating mechanism of the type first described for the approximate vertical adjustment of the slide.

Manual cross feed or wheel slide.—The grinding wheel W and its shaft 35 are supported, as previously explained, in eccentrically mounted bearings in the wheel slide 34. This slide consists of a heavy transversely extending casting having inclined bearing surfaces 85 and 86 (Figs. 7 and 8) engaging a correspondingly shaped way 87

formed integrally with the movable head 33. An adjustable gib 88 is also provided upon the wheel slide engaging an additional under-cut guide or way upon the head. By adjustment of this gib a close sliding fit of the slide upon the movable head may be secured.

The wheel slide is extended outwardly from the movable head to afford a support 10 for the eccentric bearings of the wheel shaft and also to form an integral cover or casing 89 (Fig. 8) inclosing the upper portion of the grinding wheel. A suitable cover plate 90 (Fig. 7) incloses the connections from 15 the hand wheel 82 to the eccentric sleeve 75, and at the left hand end, as viewed in Figs. 5 and 6, the wheel slide is provided with an extension or cover plate 91 for protecting the end of the supporting ways 87.

20 For moving the grinding wheel transversely of the table we provide the mechanism shown in Figs. 15, 16 and 17. This mechanism comprises a horizontal shaft 100 (Fig. 15) having one end mounted in anti-friction thrust bearings 101 in a casing 102 secured to the end of the slide-supporting portion of the movable head 33.

The shaft 100 is threaded to engage a nut 103 (Fig. 8) secured to the wheel slide 34. 30 A beveled gear 104 (Fig. 15) is mounted on the end of the shaft 100 and engages a second beveled gear 105 upon the upper end of a vertical shaft 106. At its lower end the shaft 106 has a sliding key connection 35 with a sleeve 107 mounted to rotate in a gear box 108 mounted upon the side of the bed 30. Beveled pinions 109—110 connect the sleeve 107 with a horizontal shaft 111 extending transversely through the bed to 40 the front of the machine.

Near the forward end of the shaft 111 spur gears 112 and 113 are mounted for free rotation thereon, these gears being separated by a thin cylindrical shell 114 surrounding 45 the shaft 111 between the gears. Upon their adjacent faces the gears 112 and 113 are provided with clutch teeth adapted to engage corresponding teeth upon a sliding collar 115 (Fig. 16) mounted between the gears.

50 The position of the collar 115 is controlled by a rod 116 (Fig. 15) having a knob 117 at its outer end. At its inner end the rod 116 is slotted to receive a cross key 118 which is slidable therethrough and is retained in operative position by a spring 119 mounted in a recess in the shaft 111 and engaging a notch in the side of the key.

The collar 115 is slotted to receive the key 118 while the shaft 111 and the cylindrical shell 114 are provided with elongated slots which permit longitudinal movement of the rod and key. In this manner the position of the sliding collar may be manually adjusted to connect either of the gears 112 or

113 to the shaft 111, or, if desired, the collar may be placed in a neutral position between the gears.

The gear 113 engages a pinion 120 formed upon the end of a sleeve 121 rotatable upon a fixed stud 122, and the gear 112 engages 70 a pinion 123 mounted upon the sleeve 121. The gear 123 also meshes with a gear 124 upon a short shaft 125, upon the outer end of which is mounted a hand wheel 126. These connections constitute means for feeding the wheel slide manually transversely of the table, with either a coarse or a comparatively fine feed.

In grinding operations of the character for which this machine is designed, the 80 usual hand feed of the wheel takes place after the table reaches its limit of travel, at which point the wheel is given a feeding movement of considerable magnitude. To accomplish this coarse feed, the gear 112 is 85 connected to the shaft 111. At other times it is necessary to dress the face of the wheel, for which purpose a slow continuous feed is desired and for dressing the wheel I utilize the fine feed connections through the pinion 90 120 and the gear 113.

When the power feed is in use the clutch collar may be placed in neutral position as above mentioned leaving the hand wheel and the gears connected thereto motionless.

Power cross feed of wheel slide.—For rotating the shaft 111 by power, I provide a ratchet wheel 130 (Figs. 1 and 15) keyed to the end of the shaft 111 and secured in position thereon by a nut 131. A reversible pawl 132 is pivotally mounted upon a disk 133 in position to engage the teeth of the ratchet wheel 130. The pawl is retained in either of its operative positions or in neutral position by a spring-pressed plunger in 105 the disk 133 (Fig. 15).

The disk 133 is mounted upon a sleeve 134 rotatable upon an extension 135 of a bearing bushing 136. The bushing 136 is rotatably mounted in a circular opening in the frame 110 member 137 secured to the bed and is retained therein by a ring 138. The sleeve 134 is provided with gear teeth 139 positioned to engage a sliding rack 140 (Figs. 16 and 17).

The rack 140 is slidably supported in a 115 guide 141 secured to the outer face of the bushing 136. At its opposite end the rack is connected to a crank pin 142 (Fig. 21) adjustable radially in a slot 143 (Figs. 1 and 21) in a disk 144. The crank pin is secured 120 in adjusted position by a nut 145 having a handle 146.

The disk 144 is rotated through substantially one complete revolution at each end of the table travel, these rotations alternating in direction. The mechanism for thus intermittently rotating the disk 144 will be hereinafter described. Such rotation of the

disk 144 and crank pin 142 produces intermittent reciprocating movements of the rack 140 which in turn rotates the disk 133 alternately in opposite directions.

5 During the movement in one direction the reversible pawl 132 will pass freely over the teeth on the ratchet wheel but when moving in the opposite direction the pawl 132 will engage the teeth on the ratchet wheel and 10 will rotate the shaft 111 and its connected mechanism to feed the grinding wheel W transversely of the table.

Table speed-changing and reversing-mechanism.—The main power shaft 37 (Fig. 3) 15 carries a small pulley 150 in addition to the pulleys 38 and 41 previously described. The pulley 150 is belt connected to drive a pulley 151 upon a short shaft 152 (Fig. 16), mounted in a gear box 153 (Figs. 3 and 18) secured to the rear side of the bed 30. The shaft 152 carries a worm 154 (Fig. 18) which engages a worm wheel 155 on a horizontal shaft 156 extending longitudinally of the gear box and having fixed thereto change 20 gears 157^a, 157^b and 157^c. These change gears mesh with corresponding gears 158^a, 158^b, and 158^c loosely rotatable upon a hollow shaft 159 (Fig. 19) supported in bearings 25 in the gear box 153 and parallel to the shaft 156.

The change gears 158^a, 158^b and 158^c are selectively connected to the hollow shaft 159 by a sliding key 160 pivoted to a rod 161 sliding within the shaft 159. The key is 35 movable by means of the rod into position to engage a keyway within either one of the change gears and it is yieldingly forced outward by a spring 162. A cross pin 163 engages a keyway in the hollow shaft and prevents relative rotation of the rod and shaft.

40 At its outer end, the rod 161 is provided with circumferential rack teeth 164 positioned for engagement by a pinion 165. The pinion 165 is formed upon the end of a shaft 45 166 (Fig. 16) extending horizontally to the front of the machine and having a small hand wheel 167 secured to its forward end. By proper manipulation of the hand wheel 167 the rod 161 may be moved longitudinally 50 to connect either one of the pairs of change gears to the hollow shaft 159.

A pair of oppositely disposed beveled pinions 168 and 169 (Fig. 18) are loosely mounted upon the hollow shaft 159 and are 55 provided with hub extensions having clutch teeth formed thereon. A clutch collar 170 is slidably but non-rotatably mounted upon the hollow shaft between the beveled pinions and is provided at each end with clutch teeth 60 adapted to engage the teeth upon the hubs of the pinions.

The sliding collar is controlled by a yoke member 171 (Figs. 18 and 21) mounted to slide longitudinally upon a shaft 172. The

longitudinal position of the yoke is determined by an arm 173 mounted upon a sliding rod 174 and having a depending portion engaging a collar 175 loose upon the rod 172 which supports the yoke member 171. Springs 177—177 (Fig. 18) engage the collar 175 and normally position it centrally with reference to the yoke member 171. The sliding rod 174 is connected to an arm 178 (Figs. 16 and 18) secured to a reversing shaft 179 extending forwardly to the front 75 of the machine.

At its forward end, the shaft 179 is provided with a lever 180 (Fig. 1) projecting upwardly in the path of dogs 181 secured to the side of the table 182. These dogs alternately engage the lever 180 as the table reaches its limit of travel and through the shaft 179 move the rod 174 longitudinally in one direction or the other. As the rod 174 is moved longitudinally it carries the collar 175 with it and compresses one of the springs 177. At the same time one of a pair of latches 183—183 pivoted upon the gear box 153 engages one end of the sliding yoke 171 and prevents movement thereof until a cam block 184 carried by the rod 174 engages and lifts the end of the latch to release the sliding yoke. The compressed spring 177 then acts to move the sliding yoke longitudinally, thus changing the driving relation of the clutch collar 170 to the gears 168 and 169.

The devices above described for varying the speed and reversing the direction of travel of the work table constitute no part of my invention and any other suitable speed changing and reversing mechanism may be substituted therefor.

Table reciprocating mechanism.—The beveled pinions 168 and 169 (Figs. 16 and 21) 105 are in constant engagement with a beveled gear 190 mounted upon the end of a horizontal shaft 191. The shaft 191 extends freely through the hub of a spiral gear 192 and has fixed at a point beyond the hub one 110 member 193 of a friction clutch. The member 193 is provided with an expandable friction ring 194 which when expanded engages a flange 195 formed upon the side of a gear 196 secured to the hub of the spiral gear 115 192. A clutch operating collar 197 is slideable upon the hub of the clutch member 193 and is controlled by an arm 198 pivoted at 199 and controlled by an operating handle 200.

Referring to Figs. 22 and 23 we make the following provision for feeding the table by hand. The gear 196 above described meshes with the gear 201 upon a horizontal shaft 202 mounted in fixed bearings in the 125 frame of the machine and having a second gear 203 secured thereto. The gear 203 meshes with a pinion 204 upon a second

short horizontal shaft 205 extending forwardly through the framework and having a hand wheel 206 upon its forward end. Through this train of reducing gearing the 5 operator is enabled to turn the spiral gear 192 to move the table, through connections to be described, and it should be noted that during this operation the spiral gear 192 turns freely upon the shaft 191. Accordingly 10 it is not necessary for the operator to rotate the shaft 191 or the beveled gears 190, 168 and 169 when moving the table by hand.

Power cross-feed connections.—At the forward end of the shaft 191 provision is 15 made for frictionally engaging and driving the rack-operating disk 144 previously described. For this purpose a driving member 210 (Fig. 21) is supported within a bearing 211, the member 210 being keyed to 20 the forward end of the shaft 191 and providing a support therefor. The member 210 is retained in the bearing 211 by a collar 212 and a nut 213. The hub of the member 210 is reduced at its front end to 25 form a cylindrical projection 214 upon which is rotatably supported the hub 215 of a plate 216 having the disk 144 fixed to its outer surface. A friction ring 217 (Figs. 21, 24 and 25) is mounted to rotate with the 30 plate 216 and frictionally engages an annular flange 218 upon the driving member 210. The friction band 217 is severed at one point in its circumference, as shown in Fig. 24, the two parts being yieldingly pressed 35 together by a spring 219 mounted upon a stud 220 extending loosely through one portion of the friction ring and threaded into the second portion. A radially extending pin 221 is pivotally mounted in a cylindrical 40 recess formed between the two ends of the friction ring, the pin 221 being positioned to engage a stop 222 (Fig. 16) as the ring is rotated.

The operation of this device is as follows:—The pin 221 normally engages the stop 222 and acts as a lever to separate the ends of the friction ring, thereby enlarging the ring and releasing it from driving engagement with the flange 218 upon the driving member 210. When the rotation of the shaft 191 is reversed by the engagement of one of the dogs upon the table with the reversing lever 180, the pin 221 will be moved from its stop thereby permitting the friction 55 band to contract and to come into driving engagement with the flange 218. The friction ring together with the plate 216 and the disk 144 will thereafter rotate with the driving member 210 until the parts have 60 substantially completed one revolution when the pin 221 will again engage the stop 222 upon the opposite side thereof and the friction ring will be again released from the driving flange. The plate 144 will therefore

receive substantially one revolution at each 65 reversal of the table and these revolutions will be alternate in direction. Each revolution of the disk 144 in either direction causes one complete reciprocation of the rack 140 which in turn through the connections previously described actuates the cross feed for 70 the grinding wheel.

Table driving connections.—The connections for driving the table 182 (Fig. 21) from the shaft 191 include the spiral gear 75 192 which meshes with and drives a co-operating spiral gear 230 (Fig. 16) loosely mounted upon a shaft 231 which is diagonally disposed with relation to the travel of the table and is supported in fixed bearings 80 232 secured to the bed 30.

The spiral gear 230 is frictionally connected to the shaft 231 by the devices shown in Fig. 20, which include a leather friction washer 233 engaging the hub of the gear 85 230 and forced into engagement therewith by a spring-pressed plate 234. The plate 234 has studs 235 mounted on the rear face thereof and received within recesses 236 in a collar 237 keyed to the end of the shaft 90 231 and secured thereon by lock nuts 237a. Spiral springs 238 within the recesses 236 force the plate 234 and the friction washer 95 against the hub of the gear 230. The shaft 231 is thus normally driven by the gear 230 95 but may yield with relation thereto should any obstruction interfere with the table travel.

A spiral gear 239 (Fig. 16) is slidably mounted near the forward end of the shaft 100 231, said gear being provided with anti-friction thrust bearings 240 at each end thereof, said bearings being yieldingly held in position by thick leather washers 241. The spiral gear 239 directly engages a rack 105 242 (Figs. 16 and 21) secured to the lower side of the table 182. The leather washers 241 are intended to have a substantial cushioning effect at the moment of reversal of the table travel, thereby relieving somewhat 110 the strain upon the teeth of the rack 242 and the spiral gear 239. Furthermore the sliding connection of the gear 239 and the shaft 231 prevents possible longitudinal movement of the shaft 231 by the reversal strain, 115 which movement might injure the teeth of the spiral gears 230 and 192.

Operation.—The operation of our improved grinding machine has been indicated at various points in the preceding description and need be only briefly summarized at this point. The work is secured upon the upper surface of the table 182 in any convenient manner and the grinding wheel W is brought to approximate vertical position 120 by the use of an operating handle upon the squared end 66 (Fig. 11) of the shaft 65, effective through its connections to rotate 125

the elevating screw 56, to move the head 33 to approximate position. The movable head is then clamped rigidly to the standard 31 by tightening the binding screws 54 (Fig. 2) and the final close vertical adjustment of the grinding wheel is secured by slightly rotating the eccentric bearings of the wheel shaft by manipulation of the hand wheel 82 (Figs. 6 and 10). The knob 117 (Fig. 15) may then be pulled out to connect the cross-feed hand-wheel 126 through the gears 124, 123 and 112 to the shaft 111, which in turn is connected through the shaft 106 to the cross-feed screw 100. Manipulation of the hand wheel 126 is then effective to move the grinding wheel W to its proper transverse position.

Should a finer hand cross-feed be desired, the knob 117 may be pushed in to engage 20 the gears 120 and 113 with the shaft 111. When the wheel is properly positioned transversely the knob 117 may be moved to place the clutch collar 115 in neutral position this disconnecting the hand wheel from the 25 shaft 111.

The desired table speed can be determined by selectively operating the change-gear hand-wheel 167 (Fig. 16) which controls the sliding key within the change gears 158^a, 30 158^b, and 158^c. The table 182 may be moved longitudinally by the hand wheel 206 (Fig. 23) to the desired starting position, after which the power feed may be thrown in by depressing the friction clutch lever 200 (Fig. 21). The table will thereafter be reciprocated with an automatic reversal at each end of its travel and at each reversal the cross feed rack 140 (Figs. 16 and 17) 35 will be actuated to feed the grinding wheel 40 transversely of the table.

Having thus described our invention it will be evident that changes and modifications may be made therein without departing from the spirit and scope thereof as set 45 forth in the claims and we do not wish to be otherwise limited to the details herein disclosed, but

What we do claim is:—

1. A grinding machine having in combination a movable work table, a grinding wheel and shaft supported above said table in a vertically movable head, means for elevating said head, and additional means for vertically adjusting said wheel and shaft relative to said table, said additional means comprising eccentric bearings for said shaft in said head, and manually operated devices for angularly moving said bearings.

2. A grinding machine having in combination a movable work table, a grinding wheel and shaft supported above said table in a vertically movable head, means for elevating said head, and additional means for vertically adjusting said wheel and shaft

relative to said table, said additional means 65 comprising eccentric bearings for said shaft in said head, and manually operated devices for angularly moving said bearings, the axes of said shaft and said bearings being separated a substantial distance and being so 70 relatively disposed that angular movement of said bearings will cause substantially proportional vertical movement of said shaft.

3. A grinding machine having in combination a movable work table, a grinding 75 wheel and shaft supported above said table in a vertically movable head, means for elevating said head, and additional means for vertically adjusting said wheel and shaft relative to said table, said additional means 80 comprising eccentric bearings for said shaft in said head, and manually operated devices for angularly moving said bearings, said devices comprising a gear fixed to said bearings, a hand wheel on said head, and driving 85 connections from said hand wheel to said gear.

4. A grinding machine having in combination a movable work table, a grinding 90 wheel and shaft supported above said table in a vertically movable head, means for elevating said head, and additional means for vertically adjusting said wheel and shaft relatively to said head, said means comprising an eccentric bearing for said shaft, a 95 second eccentric bearing alined with the first bearing, and means to angularly move said bearings simultaneously.

5. A grinding machine having in combination a movable work table, a grinding 100 wheel and shaft supported above said table in a vertically movable head, means for elevating said head, and additional means for vertically adjusting said wheel and shaft relatively to said head, said means comprising an eccentric bearing for said shaft, means to angularly adjust said bearing, a second eccentric bearing alined with the first bearing, and an arm connecting said bearings and constraining them to move simultaneously.

6. A grinding machine having in combination a bed, a table movable on said bed, a standard supported by said bed, a movable head vertically adjustable on said standard, 115 and having guiding ways formed thereon with the front bearing surface thereof inclined rearwardly downwardly, and a wheel slide having a correspondingly inclined bearing surface co-operating with said ways 120 and said inclined surface.

7. A grinding machine having in combination a bed, a work table movable on said bed, a standard supported on said bed, a head movable vertically on said standard, a 125 wheel slide movable horizontally on said head, a grinding wheel and shaft rotatably mounted in horizontal bearings in said slide,

and means for rotating said shaft, said means comprising a main shaft mounted in the bed, a driving pulley thereon, a guide pulley on said standard, means to adjust 5 said guide pulley vertically and to retain said pulley in adjusted position, a pair of guide pulleys mounted on the head and movable therewith, a drum on the wheel shaft, and a single long belt connecting all of said 10 pulleys and said drum.

8. A grinding machine having in combination a bed, a work table movable on said bed, a standard supported on said bed, a head movable vertically on said standard, a 15 wheel slide movable horizontally on said head, a grinding wheel and shaft rotatably mounted in horizontal bearings in said slide, and means for rotating said shaft, said means comprising a main shaft mounted in 20 the bed, a driving pulley thereon, a pair of guide pulleys mounted on the head and movable therewith, a third guide pulley mounted on a pivot secured to said standard near its upper end, a drum on the wheel shaft, 25 and a single long belt connecting said pulleys and drum, said driving pulley and said guide pulleys being so positioned that the runs of the belt from the driving pulley and the fixed guide pulley to the movable guiding pulleys are substantially vertical, whereby 30 vertical adjustment of the head requires no change in the length of the driving belt.

9. A grinding machine having in combination a bed, a table longitudinally movable 35 on said bed, a standard supported on said bed, a movable head vertically adjustable on said standard, a grinding wheel and shaft supported on said movable head, separate means for course and fine adjustment of said 40 wheel and shaft vertically, manually-operated means for fast and slow adjustment of the wheel and shaft longitudinally, and additional power-actuated means for adjusting said wheel and shaft longitudinally.

45 10. A grinding machine having in combination a bed, a table movable on said bed, a standard supported by said bed, a movable head vertically adjustable on said standard, guiding ways on said head, a wheel slide 50 longitudinally movable on said ways, and means for moving said slide, said means comprising fast and slow speed hand-operated devices, means for connecting either device to move the slide, and intermittently 55 operated power-actuated devices for automatic feeding of the wheel slide.

11. In a grinding machine, a table, a rack 60 on the table, a spiral gear engaging said rack, a diagonally-disposed shaft upon which said gear is slidably mounted, and cushioning members disposed at each end of said spiral gear to relieve the end thrust thereon when the table is reversed.

12. In a grinding machine, a table, a rack

on the table, a spiral gear engaging said 65 rack, a diagonally disposed shaft upon which said gear is mounted, a second gear loosely supported on said shaft, means for driving said gear, and friction connections between said gear and said diagonal shaft. 70

13. In a grinding machine, a table, a rack on the table, a spiral gear engaging said rack, a diagonally-disposed shaft upon which said gear is mounted, a second spiral gear upon the diagonal shaft, a transversely-extending horizontal shaft disposed below said diagonal shaft, a third spiral gear meshing with said second gear and rotatable upon the transverse shaft, a friction clutch between said shaft and said third gear, and 80 means for rotating said transverse shaft.

14. In a grinding machine, a table, a rack on the table, a spiral gear engaging said rack, a diagonally disposed shaft upon which said gear is mounted, a second spiral 85 gear upon the diagonal shaft, a transversely-extending horizontal shaft disposed below said diagonal shaft, a third spiral gear meshing with said second gear and rotatable upon the transverse shaft, a friction clutch between said shaft and said third gear, and means for rotating said transverse shaft, said means including devices for automatically reversing said shaft and for varying 90 the speed thereof. 95

15. In a grinding machine in combination a table, a rack on said table, a shaft, connections from said shaft to said rack, means to drive said shaft in either direction by power, and means to move the table manually 100 through said connections but independently of said shaft.

16. In a grinding machine, a shaft, table driving mechanism, means for frictionally engaging and driving said mechanism from 105 said shaft, a wheel slide, mechanism for moving the wheel slide longitudinally, and connections for intermittently actuating said latter mechanism from said shaft.

17. In a grinding machine, a table, a 110 grinding wheel, mechanism for feeding the wheel transversely of the table, and devices for intermittently actuating said mechanism, said devices comprising a pinion, a rack engaging said pinion, a crank pin forming a 115 pivot for said rack and adjustably mounted on a crank disk, and means for intermittently rotating said disk substantially one revolution at each reversal of the table travel. 120

18. In a grinding machine, a table, a grinding wheel, mechanism for feeding the wheel transversely of the table, and devices for intermittently actuating said mechanism, said devices comprising a pinion, a 125 rack engaging said pinion, a crank pin forming a pivot for said rack and adjustably mounted on a crank disk, means for inter-

mittently rotating said disk, and an angularly movable support for said rack mounted concentrically with said pinion and effective to hold said rack in operative engagement with said pinion during the rotation of the crank disk and pin.

In testimony whereof we have hereunto

set our hands, in the presence of two subscribing witnesses.
